(57) **CLAIM**

The ornamental design for a collapsible organizer, as shown and described.

DESCRIPTION

FIG. 1 is a right side view of a collapsible organizer, the collapsible organizer is in an open condition to show my new design.

FIG. 2 is a top view thereof with a center compartment flap closed.

FIG. 3 is a top view thereof with the center compartment flap open.

FIG. 4 is another side view thereof, wherein the collapsible organizer is in a compressed state with two compartments where the middle compartment is compressed.

FIG. 5 is a top view thereof.

FIG. 6 is another side view thereof wherein the collapsible organizer is in a compressed state with two compartments where an end compartment is compressed.

FIG. 7 is a top view thereof.

FIG. 8 is another side view thereof, wherein the collapsible organizer is in a compressed state with two compartments where the other end side compartment is compressed.

FIG. 9 is a top view thereof.

FIG. 10 is another side view thereof, wherein the collapsible organizer is in a collapsed state with one compartment.

FIG. 11 is a top view thereof.

FIG. 12 is a perspective view of the collapsible organizer, wherein the collapsible organizer is in a fully closed and collapsed state.

FIG. 13 is a front view thereof.

FIG. 14 is a rear view thereof.

FIG. 15 is a right side view thereof.

FIG. 16 is a left side view thereof.

FIG. 17 is a top view thereof.

FIG. 18 is a bottom view thereof.

FIG. 19 is a right side view thereof, wherein two top hard covers are installed on the side compartments.

FIG. 20 is a top view of the first side compartment.

FIG. 21 is a top view of the second side compartment.

FIG. 22 is a bottom view of the first side compartment.

FIG. 23 is a bottom view of the second side compartment.

FIG. 24 is another side view of the collapsible organizer wherein the collapsible organizer is in an opened state and has two hard covers on.

FIG. 25 is a right side view of an alternate embodiment of a collapsible organizer, the collapsible organizer is in an open condition.

FIG. 26 is a top view thereof with a right compartment flap closed.

(Continued)

FIG. 27 is a top view thereof with a right compartment flap open.

FIG. 28 is another side view thereof, wherein the collapsible organizer is in a compressed state with two compartments where the middle compartment is compressed.

FIG. 29 is a top view thereof.

FIG. 30 is another side view thereof wherein the organizer is on a compressed state with two compartments where an end compartment is compressed.

FIG. 31 is a top view thereof.

FIG. 32 is another side view thereof, wherein the collapsible organizer is in a compressed state with two compartments where the other end side compartment is compressed.

FIG. 33 is a top view thereof.

FIG. 34 is another side view thereof, wherein the collapsible organizer is in a collapsed state with one compartment.

FIG. 35 is a top view thereof.

FIG. 36 is a perspective view of the collapsible organizer, wherein the collapsible organizer is in a fully closed and collapsed state.

FIG. 37 is a front view thereof.

FIG. 38 is a rear view thereof.

FIG. 39 is a right side view thereof.

FIG. 40 is a left side view thereof.

FIG. 41 is a top view thereof.

FIG. 42 is a bottom view thereof.

FIG. 43 is a right side view thereof, wherein a top hard cover is installed.

FIG. 44 is a top view thereof.

FIG. 45 is a bottom view thereof; and,

FIG. 46 is another side view of the collapsible organizer wherein the collapsible organizer is in an opened state and has a hard cover on.
